UNITED STATES PATENT OFFICE.

FRANK B. WILDMAN, OF NORRISTOWN, PENNSYLVANIA, ASSIGNOR TO THE McMICHAEL & WILDMAN MANUFACTURING COMPANY, OF PENNSYLVANIA.

PATTERN MECHANISM.

SPECIFICATION forming part of Letters Patent No. 642,402, dated January 30, 1900.

Application filed July 19, 1899. Serial No. 724,405. (No model.)

To all whom it may concern:

Be it known that I, FRANK B. WILDMAN, a citizen of the United States, residing at Norristown, Pennsylvania, have invented certain new and useful Improvements in Pattern Mechanism, of which the following is a specification.

My invention is an improvement in pattern mechanisms for knitting-machines designed for measuring off the desired length of fabric of any particular style of knitting and for changing the character of the stitch as called for by the pattern or style of garment to be produced.

In carrying out my invention I arrange my pattern mechanism to be carried by and travel with the moving parts of the machine, and I have shown it as carried by the rotating take-up mechanism being supported on the rotary take-up plate to travel or rotate with the cylinder. I do not wish to limit myself, however, to the type of machine in which the needle-bed travels.

In the drawings, Figure 1 is a side elevation of the machine with parts in section and parts removed. Fig. 2 is a detail sectional view on line 2 2 of Fig. 3. Fig. 3 is a plan view with parts in section, the upper structure being omitted.

In the drawings, 1 represents the cylinder, which is operated by the gear 3 through any suitable driving connections. The cylinder and adjacent parts are supported by the standards 4, connected at their lower ends with a fixed base-ring 5. This fixed base-ring supports a take-up plate 6, which rotates on a flange 7 of the base-ring. This take-up plate is rotated in unison with the cylinder, being connected therewith by the standards 8. These standards have bearings in which the take-up rolls 9 are journaled. The pattern wheel or ring consists of a ring or plate 11, carried by the movable section 10 of the take-up plate 6. This section of the take-up plate is seated on the flange 12 of said plate, and it rotates with the take-up plate and cylinder. The pattern-wheel is held to the section 10 of the take-up plate by the clips 13, and springs 14 serve to put the pattern-wheel under frictional restraint, so that it will rotate

with the take-up plate, but is yet adapted to have rotary movement independent of the take-up ring or plate. The take-up ring rotates in the direction of the arrow *a* in Fig. 3. It has gear-teeth 16 on its edge meshing with 55 a pinion 17, journaled in the fixed base-ring 5. The pinion also meshes with gear-teeth on the section 10 of the take-up ring, and as the teeth of this section are one more in number than the teeth on the main part of the 60 take-up ring the said section will be rotated or moved on the take-up ring the distance of one tooth for each revolution of the machine, and this rotation will be in the direction of the arrow *b* or backward in relation to 65 the direction of rotary motion of the take-up ring. This slow motion of the section 10 on the rotating take-up ring is imparted to the pattern wheel or ring, for, as before stated, the pattern-wheel is in frictional engagement 70 with the section 10 by means of the clips 13 and the springs 14. It will thus be seen that while the pattern-wheel rotates with the take-up plate and cylinder of the machine it has in addition a slow movement on and in relation to the take-up plate, so that its pattern-controlling studs or cams are advanced slowly toward the connections which are to be operated thereby, a part of which connections are also carried on the take-up plate. The 75 pattern-wheel has cam or pattern studs 18 with beveled tops, which are adapted to be placed in any one of the series of holes 19 with which the pattern-wheel is provided. The slow movement of the pattern-wheel on 80 the take-up plate will after the predetermined interval bring one of the cam-studs to the lever 20, which is pivoted at 21 on the take-up plate, so as to move therewith and bear a fixed relation thereto. This lever has 85 an arm 22, connected with a rod 23, extending vertically and connected with the slide 24, which carries at its upper end a roller or disk 25. The slide is guided in a bracket 26 of one of the cylinder-standards, and the lever 90 is held up normally at its inner end by a spring 27, so that the rod will be held elevated, together with the roller. So long as 95 this position is maintained the machine will do one kind of knitting, as the roller is then 100

in the plane of an arm 28, attached to a rock-shaft 29, having suitable bearings at 30 in the fixed frame and connected at its upper end by a rod 31 with the controlling means for 5 the needle-cams. When the roller or disk 25 is lowered, it will then be in the plane of an arm 28', which is carried by a pin journaled in the bearing 30 and having a geared connection at 32 with the shaft, so that when 10 the latter arm is struck it will return the shaft 29 to its former position, and the machine will then do another kind of knitting. The depression of this roller is controlled by the pattern-studs and pattern mechanism, 15 for when a pattern-stud is forced under the end of the lever it will be lifted, and thus the roller will be depressed.

As before stated, the slow movement of the pattern wheel or disk on the rotary take-up 20 plate, due to the differential gearing, will bring one of the pattern-studs to the lever 20, which is also carried by the rotary plate, and in order to force the cam or pattern stud under the end of the lever I employ a spring- 25 pawl 35, carried by a lever 36, pivoted to the stud 37, carried by the take-up plate and having its end in the path of a stud or studs 38, fixed to the fixed base-ring 5, so that the pawl will be operated, as shown, once at each 30 revolution of the machine, or more frequently, if desired. The pattern wheel or ring has ratchet-teeth 39 on its edge, and guard-plates 40 are secured to the pattern wheel or ring to cover certain of the teeth and prevent the 35 movement of the pawl from having any effect on the pattern-wheel, except at intervals determined by the pattern to be formed. These guard-plates are removed, therefore, from those teeth which are to be effective in operating the pattern-wheel. The pattern-studs and these uncovered teeth bear such a relative position to each other on the pattern-wheel that when the pattern-stud has arrived 40 at the lever 20, as shown in Fig. 3, by reason of the slow movement of the pattern-wheel on the take-up plate the pawl falls into the uncovered tooth, as shown in said Fig. 3, and then the rotation of the machine will cause the pawl-lever to strike the pin 38, and the 45 pattern-wheel will then be given a quick movement by the pawl, thus forcing the stud under the lever 20 and operating the said lever to change the pattern or style of knitting through the connections described. The frictional resistance between the pattern-wheel 50 and take-up-plate section 10 is overcome by the stronger action of the pawl, and the action is rendered certain and definite. The end of the lever 20 is beveled to permit the 55 cam-stud to be forced under it. The lever has an extension 20', so as to cover two cam-studs at once and prevent vibration by the lever falling in between the studs. The pawl having shifted the pattern-wheel to cause the 60 quick operation of the connections leading to the needle-cam-controlling means, the pat-

tern-wheel will now continue its slow movement on the rotating take-up plate until another cam-stud reaches the operating-lever, at which time the pawl will find an uncovered 70 tooth in the pattern-wheel, and the pawl-arm striking the pin will cause the pattern-wheel to be shifted quickly for changing the pattern. If a pattern is being worked which does not call into use all parts of the pattern-wheel, 75 the wheel may be moved around quickly to the point of starting after the pattern is finished by leaving off the guard-plates from the ratchet-teeth. The pawl will then be effective on every tooth lying between the end and the 80 beginning of the pattern.

The pattern may be varied so as to call for two, three, or more different kinds of stitches, so that while the machine is knitting the disk 25 will need to be elevated and depressed to 85 different planes in order to shift it into line with either of two or more sets of levers which connect with the controlling devices of the needle-cams—as, for instance, for producing loose courses, welts, tucking or cardigan stitch—and to accomplish this the pattern-studs would be different heights. The pattern-wheel being held simply by friction can be moved by hand forward or backward to the starting-point at any time. 95

From the above it will be seen that the take-up plate and its section 10 form part of the pattern mechanism. This pattern mechanism, considered as a whole, travels in unison with the needle-bed; but in addition to 100 this movement in unison a part of the pattern mechanism—i. e., the wheel—has a slow movement either forward or backward in relation to the take-up plate and cylinder. By my invention I provide a combined take-up 105 and pattern mechanism, as the take-up plate performs a twofold function, it being employed in a well-known manner through gearing 41 42 to support the take-up mechanism and by its rotation to operate it and also performing the functions set forth above in connection with the pattern mechanism. 110

It will be seen that the take-up plate or ring forms a traveling carrier for the pattern-wheel and also for the take-up-mechanism, and both 115 of these mechanisms are operated through gearing which is in connection with the main frame of the machine.

The pawl-lever 36 is under tension of the spring 50, which returns it after each operation against the stop-pin 51.

I claim as my invention—

1. In combination with a knitting-machine having a traveling part, pattern mechanism comprising a carrier with adjustable pattern 125 pins or studs having traveling movement with said part, means whereby the traveling movement of the pattern mechanism will cause the same to be operated, and connections operated by the studs or pins in succession for 130 changing the pattern, substantially as described.

2. In combination in a circular-knitting machine having a rotary part, means for adjusting the needle-cams to alter the pattern, connections leading to said means, and pattern mechanism arranged apart from the cam ring and cylinder and rotating with the traveling part of the machine and arranged also to operate the said connections, said pattern mechanism comprising adjustable parts to alter the pattern and means whereby the traveling movement of the pattern mechanism will cause the same to be operated, substantially as described. 5
3. In combination in a knitting-machine, a traveling part and pattern mechanism traveling in unison with the said part and having a series of pattern-studs, said pattern mechanism being provided with a portion having a slow movement in addition to said traveling movement whereby the pattern-studs are brought into position for operation and means for imparting said slow movement as the pattern mechanism travels, substantially as described. 10
4. In combination in a circular-knitting machine, a pattern mechanism having adjustable pattern pins or studs and arranged concentric with the machine operating means therefor, and connections to be operated by said studs in succession, substantially as described. 15
5. In combination with a circular-knitting machine, pattern mechanism rotating with the machine and arranged concentric in relation to the axis thereof with means for moving said pattern mechanism continuously as the machine rotates, substantially as described. 20
6. A circular-knitting machine having a rotating needle-bed, a take-up mechanism rotating in unison with the fabric and pattern means rotating with the take-up mechanism and fabric, substantially as described. 25
7. In combination in a circular-knitting machine, a rotary needle-bed, a take-up mechanism for the fabric rotating in unison with the rotary movement of the needle-bed and pattern mechanism rotating with the take-up, with means for causing the operation of the pattern mechanism from said rotary movement. 30
8. In combination in a knitting-machine, the rotary needle-bed the cam-ring, a rotary pattern mechanism comprising a carrier connected to the bed to rotate therewith and a pattern or stud ring thereon, connections from the pattern mechanism to the needle-controlling cams and means for causing the operation of the pattern mechanism during said rotation, substantially as described. 35
9. In combination, the rotary needle-bed or other traveling part, a rotary pattern-wheel in connection therewith to travel with the said part and having adjustable pattern-studs, connections between the pattern-wheel and the controlling-cams, carrier means for the pattern-wheel arranged independent of the cyl- 40
- inder and cam-ring and means for giving the pattern-wheel a movement on the carrier said carrier traveling with the traveling part of the machine. 70
10. A combined pattern and take-up mechanism for knitting-machines and the like comprising a traveling part and take-up and pattern means carried thereby with means for operating the same, substantially as described. 75
11. A combined pattern and take-up mechanism for knitting-machines and the like comprising a traveling part, take-up means carried thereby, pattern means also carried thereby, a fixed frame and gearing between the same and the take-up and pattern means respectively for operating the same, substantially as described. 80
12. In combination with a knitting or like machine, a combined take-up and pattern mechanism with operating means therefor said take-up and pattern mechanism traveling with a traveling part of the machine, said pattern mechanism being operated by the said traveling movement. 85
13. A pattern mechanism for knitting-machines and the like comprising a carrier means for causing said carrier to travel in unison with a traveling part of the machine, pattern-controlling means on said traveling carrier means for giving the same a slow movement in relation to and upon the traveling carrier and means for giving said pattern-controlling means a quick movement on said carrier, substantially as described. 90
14. In combination in a circular-knitting machine, a rotary needle-bed or other part, a rotary pattern-wheel, a rotary carrier therefor traveling in unison with the needle-bed or other part, means for giving the pattern-wheel a slow movement on the rotary carrier, means for giving the pattern-wheel a quick movement on the rotary carrier and connections between the pattern-wheel and parts to be controlled, substantially as described. 105
15. In combination in a circular-knitting machine, pattern mechanism concentric with the needle-circle comprising a pattern-wheel, a rotary carrier therefor, means for giving the pattern-wheel a slow movement on said carrier, means for giving the pattern-wheel a quick movement on said carrier and connections leading from the pattern mechanism to the parts to be controlled, substantially as described. 110
16. A pattern mechanism comprising a moving carrier, a pattern device thereon, means for giving the pattern device a slow movement on the carrier, and means for giving the pattern device a quick movement on the carrier, connections from the pattern device to the parts to be controlled and take-up mechanism supported on and controlled by the movement of the carrier. 115
17. In combination, the pattern device, the carrier therefor, the differential gearing for slowly moving the pattern device on the car- 120
- 125
- 130

rier and means for giving the pattern device a rapid movement on the carrier, substantially as described.

18. In combination, the pattern-wheel having ratchet-teeth, the carrier comprising the two sections having differential gear-teeth thereon, one section being movable on the other, a gear for operating the two sections, a pawl for engaging the ratchet-teeth to operate the pattern-wheel and means for operating the pawl.

19. In combination, the pattern-wheel, having ratchet-teeth, a toothed ring having frictional engagement therewith to move the pattern-wheel, a carrier for the toothed ring, a pawl with operating means for moving the pattern-wheel and connections leading from the pattern-wheel to the parts to be controlled.

20. In combination, the pattern-wheel, a rotary carrier, having teeth, a toothed section carried thereby and having frictional engagement with the pattern-wheel, a pawl for engaging the teeth of the pattern-wheel, removable guard-plates for the said teeth, a pinion 25 engaging the teeth of the section and carrier to give the toothed section a slow movement on the toothed carrier by reason of the teeth being differential and a lever on the movable carrier to be operated by the pattern-wheel 30 and connections leading from the lever to the parts to be controlled, substantially as described.

21. In combination with the rotary cylinder, a take-up plate rotating in unison therewith, take-up means supported on said plate, a ring or section carried by the plate, with means for giving it a slow movement on the plate, a pattern-wheel carried by the section, means for giving the pattern-wheel a quick 40 movement and connections leading from the pattern-wheel to the parts to be controlled.

22. In combination, the rotary cylinder, the take-up plate, rotating with the cylinder, take-up means on the plate, a section carried by 45 the take-up plate, differential teeth on take-

up plate and section, a pinion relatively fixed and meshing with the teeth of the plate and section to give the section a movement over the plate, a pattern-wheel carried by friction on the section of the plate, said pattern-wheel 50 having ratchet-teeth, a pawl supported on the take-up plate for engaging said teeth, removable guards for shielding the teeth from engagement with the pawl and means on the fixed frame for operating the pawl, and a lever carried by the take-up plate to be operated by the pattern-wheel with connections leading from said lever to the parts to be controlled, substantially as described.

23. A pattern mechanism comprising a movable part connected to travel continuously with a traveling part of the machine, means for giving the part an additional slow movement, means for giving it a rapid intermittent movement and connections controlled 65 by said movable part, substantially as described.

24. In combination in a circular-knitting machine, with the cam ring and cylinder, a pattern mechanism rotating in a horizontal 70 plane and out of the horizontal plane of the cam ring and cylinder with means for operating the said mechanism, pattern-studs carried adjustably by the pattern mechanism and connections operated by said studs substantially as described.

25. In combination, the cam ring and cylinder, a pattern mechanism concentric with the axis thereof, said pattern mechanism rotating in a different horizontal plane from 80 that of the cam ring and cylinder and means for operating the pattern mechanism pattern-studs carried adjustably by the pattern mechanism and connections operated by said studs.

In testimony whereof I affix my signature 85 in presence of two witnesses.

FRANK B. WILDMAN.
